(57) **CLAIM**

The ornamental design for a gate keeper for a snap hook, as
shown and described.

DESCRIPTION

FIG. 1 is a left side elevational view of the gate keeper for
a snap hook;

FIG. 2 is an upper left side perspective view thereof;

FIG. 3 is a right side elevational view thereof;

FIG. 4 is a bottom view thereof;

FIG. 5 is a top plan view thereof;

FIG. 6 is a front elevational view thereof; and,

FIG. 7 is a rear elevational view thereof.

The broken line showing of the snap hook is for illustrative
purposes only and forms no part of the claimed design.
